ABSTRACT: An ignition means for a burner means of a cooking apparatus or the like which creates electrical sparks at the pilot burner means thereof, the sparks being created by the altering of the stresses in piezoelectric crystal means that is rocked relative to the supporting structure by a cam element disposed between the crystal means and an end surface of a supporting frame structure. The cam element is carried by a lever arm that is guided in its movement by cooperating surface means of the support frame.

PIEZOELECTRIC VOLTAGE SOURCE FOR IGNITION MEANS

This invention relates to an improved ignition means for burner means or the like.

It is well known that many cooking apparatus of the fuel burning variety each has an individual pilot burner means for each main burner thereof whether the main burner is disposed in the oven or on top of the cooking apparatus, the pilot burner means each being continuously burning burners and when adversely put out because of air currents or the like, the same must be reignited by the housewife, or the like, utilizing matches or the like.

However, according to the teachings of this invention, ignition means are provided for such a pilot burner means wherein the housewife or the like can initiate the actuation of the ignition means completely remote from the pilot burner means while igniting the pilot burner means in a simple and effective manner.

In particular, the ignition means of this invention includes piezoelectric crystal means that when actuated by the housewife or the like will have the stresses therein altered in such a manner that the same will cause sparking at the pilot burner means to ignite the same, the ignition means including improved means for applying a compressing or squeezing action on the piezoelectric crystal means as well as providing a relieving such compressing or squeezing action to also alter the stresses thereof.

Accordingly, it is an object of this invention to provide an improved ignition means for a cooking apparatus or the like, the ignition means of this invention having one or more of the novel features set forth above or hereinafter shown or described.

Other objects, uses and advantages of this invention are apparent from a reading of this description which proceeds with reference to the accompanying drawings forming a part thereof and wherein:

FIG. 1 is a schematic side view of the improved ignition means of this invention.

FIG. 2 is a cross-sectional view taken on line 2-2 of FIG. 1.

FIG. 3 is an exploded perspective view of various parts of the ignition means of FIG. 1.

FIG. 4 is a view similar to FIG. 1 and illustrates the various operating positions of the ignition means of FIG. 1.

FIG. 5 is an enlarged fragmentary view of the cam actuating portion of the ignition means of FIG. 4, FIG. 5 illustrating the cam member in one operating position thereof.

FIG. 6 is a view similar to FIG. 5 and illustrates the cam member in another operating position thereof.

While the various features of this invention are hereinafter described and illustrated as being particularly adaptable for providing ignition means for a cooking apparatus, it is to be understood that the various features of this invention can be utilized singly or in any combination thereof to provide ignition means for other apparatus as desired.

Therefore, this invention is not to be limited to only the embodiments illustrated in the drawings, because the drawings are merely utilized to illustrate one of the wide variety of uses of this invention.

Referring now to FIGS. 1-3, the improved ignition means of this invention is generally indicated by the reference numeral 10 and comprises a support frame 11 carrying a piezoelectric crystal means or stack 12 in such a manner that when an operating lever 13 is moved relative to the support frame 11, the crystal means 12 will cause sparking at a spark gap 14 defined by an electrode 15 and a pilot burner means 16 in a manner hereinafter described, the sparking at the spark gap 14 being adapted to ignite fuel issuing from an outlet means 17 of the pilot burner means 16 so that the ignited pilot burner means 16 can effectively ignite fuel issuing from a main burner means 18 of a cooking apparatus or the like utilizing the ignition means 10 of this invention.

As illustrated in FIG. 2, the crystal means or stack 12 comprises a pair of piezoelectric crystal elements 19 and 20

disposed in axially aligned relation with an electrical terminal 21 disposed therebetween and electrically interconnected to an insulated lead 22 leading to the electrode 15, the electrode 15 being electrically insulated from the frame structure of the cooking apparatus carrying the burner means 16 and 18.

The crystal elements 19 and 20 are confined in a suitable encapsulating or housing member 23 having suitable openings for receiving metallic anvils or pressure pad means 24 and 25 at the opposed ends thereof, the anvil means 24 and 25 being respectively disposed against the opposed ends 26 and 27 of the respective crystal elements 19 and 20.

Support frame 11 has a cutout or slot means 28 passing therethrough and defining an elongated slot 29 at the lower end 30 thereof and a guide slot 31 at the other end 32 thereof. A roller element 33 is disposed in the slot 29 of the support frame 11 and supports the crystal stack 12 by having the anvil 25 thereof bearing against the roller portions 34 of the lower element 33 for a purpose hereinafter described.

The cutout 28 in the support frame 11 defines a flat end wall 35 at the upper end of the guide slot 31 and a pair of opposed arcuate end walls 36 and 37 facing each other in spaced relation. A flat platelike member 38 having the opposed ends 39 and 40 thereof provided with notches 41 and 42 is disposed against the flat end wall 35 of the support frame 11 while the notches 41 and 42 thereof respectively receive the end walls 36 and 37 as illustrated in FIG. 1.

A cam member 43 is disposed in the guide slot 31 between the plate 38 and the flat end surface 44 of the upper anvil 24, the cam member 43 having a true partial, circular cross-sectional surface 45 concentrically disposed about the longitudinal axis 46 thereof and an upper chordal cross-sectional surface 47 joining the partial circular surface 45 to define a pair of cross-sectional corners 48 and 49 therewith.

The cam member 43 has a slot 50 interrupting the end 51 thereof with the slot 50 forming a true diameter of the cam element 43.

The actuating lever for the ignition means 10 has an upper end 52 disposed or bent at right angles relative to the main body 53 of the lever 13 and defines a guide means or member for the cam element 43. In particular, the guide part 52 of the lever 13 has a rectangular slot 54 passing therethrough and defining opposed shoulder means 55 and 56, the slot 54 being so constructed and arranged that the cam element 43 can be disposed therein and receive the shoulder means 55 in the slot means 50 thereof whereby when the guide part 52 and cam element 43 are assembled together, the same will move in unison relative to the frame 11. The guide part 52 of the lever 13 has a pair of opposed notches 57 and 58 cut therein at the respective side edges 59 and 60 to respectively define guide surface means 61 and 62 respectively receiving the opposed end wall means 36 and 37 of the support frame 11 when the lever 13 is assembled thereto as illustrated in the drawings.

Therefore, it can be seen that the various parts forming the ignition means 10 of this invention are relatively simple to manufacture and are readily adapted to be assembled together to provide spark igniting means for the burner means of a cooking apparatus or the like by operating in the following manner.

As previously stated, the electrode 15 electrically interconnected to the terminal means 21 of the crystal stack 12 cooperates with the pilot burner means 16 to define the spark gap 14 adjacent the outlet means 17 of the pilot burner 16. Since the pilot burner means 16 is formed of metallic material and is directly secured to the metallic frame structure of a cooking apparatus or the like, the pilot burner means 16 forms an electrode that is at ground potential, as indicated schematically by ground means 63 in FIG. 1, because the conventional cooking apparatus is grounded by the fuel supply conduits interconnected thereto as well as by conventional grounding means.

Thus, when the housewife or the like finds that the burner means 18 will not ignite when the fuel is directed to the main burner means 18 by the conventional selector knob means on

the cooking apparatus or the housewife or the like actually notices that no flame is existing at the pilot burner means 16, the housewife or the like will move the lever 13 in either a clockwise or counterclockwise direction as illustrated respectively in FIGS. 5 and 6 to effect sparking at the spark gap 14 to ignite the fuel issuing from the pilot burner means 16.

For example, assuming that the lever means 13 is being moved in a clockwise direction as illustrated in FIGS. 4 and 5, the guide part 52 of the lever 13 is likewise being moved in a clockwise direction and is being guided by the arcuate end walls 36 and 37 of the support frame 11 cooperating with the notches 57 and 58 so that the axis 46 of the cam element 43 will be moved in an arc that is always in substantially a equal distance relationship between the parts of arcuate end walls 36 and 37 being engaged by the guide part 52 to not only rotate the cam element 43, but also to cause the axis 46 thereof to move downwardly and to the left as illustrated in FIG. 5 as the corner 48 of the cam element 43 bears against the flat plate 38 and the partial circular surface 45 thereof rolls against the flat surface 44 of the anvil 24 of the crystal stack means 12. Since the effective length of the cam element 43 between the plate 38 and the anvil 24 is progressively increasing as the cam element 43 is, in effect, rotated in a clockwise direction with the lever 13, a compressing or squeezing action is imposed in a longitudinal manner between the opposed ends 26 and 27 of the crystal elements 19 and 20 to alter the stresses thereof. As the cam element 43 is rotating in a clockwise direction, it can be seen that the crystal stack 12 rocks therewith in a counterclockwise direction on the roller means 33 so that the longitudinal axis of the crystal stack means 12 moves from the true vertical position as illustrated generally by the reference numeral 64 in FIGS. 4 and 5 to the angular position generally indicated by the reference numeral 64A in FIGS. 4 and 5 so that the compressing and squeezing action being imposed by the cam member 43 on the crystal elements 19 and 20 will not adversely affect the same while still effectively altering the stresses thereof to produce the aforementioned sparking at the spark gap 14.

In particular, as the stresses in the crystal elements 19 and 20 are being altered in the above manner, a potential difference is being created at the electrode 15 and the grounded electrode 16 so that when such differences in potential reaches a certain magnitude, electric sparking or arcing will be created therebetween at the spark gap 14 to ignite the fuel issuing from the outlet means 17 of the pilot burner means 16. Such sparking at the spark gap 14 can occur one or more times at the spark gap 14 during the clockwise rotation of the cam element 43. After the cam element 43 has been rotated in a clockwise direction a certain amount, merely releasing the lever 13 will permit the crystal stack 12 to exert an expanding force to rotate the cam element 43 back to the full line position illustrated in FIG. 1 whereby such expansion of the crystal elements 19 and 20 will also alter the stresses thereof to create the aforementioned potential difference at the electrodes 15 and 16 for further sparking at the spark gap 14 one or more times.

Conversely, should the lever 14 be moved relative to the support frame 11 in a counterclockwise direction as illustrated in FIG. 6, the guide part 52 will cause a counterclockwise rotation of the cam element 43 so that the cam element 43 will rock on the corner 49 thereof to produce the aforementioned squeezing and compressing action on the crystal stack 12 while causing the crystal stack 12 to rock in a clockwise direction on the roller means 33 so that the longitudinal axis 64 thereof illustrated in FIGS. 4 and 6 will be moved from the true vertical position thereof to the angular position generally indicated by the reference numeral 64B in FIGS. 4 and 6.

In order to prevent overstressing of the crystal stack 12 during the aforementioned clocks clockwise or counterclockwise movement of the lever 13, it can readily be seen in FIG. 4 that the guide part 52 of the lever 13 will engage the lower surface of the plate 38 to prevent further clockwise or counterclockwise movement of the lever 13 relative to the frame 11.

Also, since the slot 50 in the cam element 43 receives the shoulder 55 of the guide part 52 of the lever 13 in a region closely adjacent the main body 53 of the lever 13, the torque being imposed on the cam element 43 by the clockwise or counterclockwise movement of the lever 13 is maintained close to the actuating end 53 of the lever 13.

From the above, it can be seen that the parts for forming the improved ignition means 10 of this invention can be readily assembled together to provide a rugged and accurate assembly 10 which have a relatively long life.

For example, after the cam element 43 has been disposed in the slot 54 of the guide part 52 of the lever 13 so that the shoulder 55 is fully received in the slot at one end of the cam element 43, the other shoulder part 56 of the guide part 52 15 can be staked or deformed toward the adjacent end of the assembled cam element 43 in the manner illustrated in FIG. 2 to hold the cam element 33 in assembled relation with the lever 13.

Also, after the various parts of the ignition means 10 have 20 been assembled in the stacked arrangement illustrated in FIG. 1, the frame member 11 can be staked at the opposed sides thereof in the manner illustrated by the reference numeral 65 in FIGS. 1 and 2 to upwardly deform part of the frame 11 between the opposed ends 30 and 32 thereof to lock the stacked elements 38, 43, 12 and 44 into position within the cutout relief 29 of the frame 11 as illustrated. Thus, the staked or elongationally squeezed section 65 of the frame 11 locks the assembly to the frame 11.

While the above description of the operation of the ignition means 10 has been described as the lever means 13 being moved either in a clockwise or counterclockwise direction from the position illustrated in FIG. 1, it is to be understood that the actuation of the ignition means 10 can be produced by 30 the housewife or the like moving the lever 13 in both a clockwise and counterclockwise direction to effect sparking at the spark gap 14. Thus, while it is believed that just one back and forth operation of the lever 13 will produce sufficient 35 sparking at the spark gap 14 to ignite the pilot burner 16, a mere repetitive action of the housewife or the like moving the lever means 13 will more than insure that the pilot burner means 16 will be fully ignited.

Further, while the ignition means of this invention has been 40 described as igniting pilot burner means for the cooking apparatus, it is to be understood that such ignition means can be utilized to directly ignite the main burner means of the cooking apparatus or the like without utilizing the intermediate pilot burner means therefor. Also, if it is found that the electrical 45 capacitance of the appliance is too great, the ignition means 10 of this invention could be utilized with two wires connected to spaced electrodes forming the spark gap while the ignition means 10 is insulated in any suitable manner from the frame structure of the cooking apparatus or the like.

While the form of the invention now preferred has been disclosed as required by the statutes, other forms may be used, all coming within the scope of the claims which follow.

I claim:

1. In combination, a support frame, piezoelectric crystal means carried by said support frame and being adapted to have the stresses thereof altered to create ignition sparks and the like, said crystal means having an end surface, said frame having an end surface facing said end surface of said crystal means and being spaced therefrom, a cam member disposed between said end surfaces and being in engagement therewith, and lever means secured to said cam member for rotating said cam member in unison with said lever means relative to said end surfaces to vary the distance therebetween and thereby vary the effective force of said cam member acting on said end surface of said crystal means to alter the stresses thereof, said lever means being directly guided in its movement by said frame to not only rotate said cam member and said lever means relative to said frame, but also to move the axis of rotation of said cam member and said lever means relative to said frame.

2. A combination as set forth in claim 1 wherein said cam member has a flat surface for engaging one of said end surfaces.

3. A combination as set forth in claim 1 wherein said crystal means has an opposed end surface, and roller means carried by said frame and engaging said opposed end surface.

4. A combination as set forth in claim 1 wherein said lever means has a portion thereof that defines a guide member carried by said cam member.

5. In combination, a support frame, piezoelectric crystal means carried by said support frame and being adapted to have the stresses thereof altered to create ignition sparks and the like, said crystal means having an end surface, said frame having an end surface facing said end surface of said crystal means and being spaced therefrom, a cam member disposed between said end surfaces and being in engagement therewith, and means for rotating said cam member relative to said end surfaces to vary the distance therebetween and thereby vary the effective force of said cam member acting on said end surface of said crystal means to alter the stresses thereof, said last-named means being directly guided in its movement by said frame to not only rotate said cam member relative to said frame, but also to move the axis of rotation of said cam member relative to said frame, said last-named means comprising a guide member carried by said cam member, said guide member having a slot passing therethrough and receiving said cam member, said slot defining a shoulder on said guide member, said cam member having a notch therein receiving said shoulder whereby said guide member and said cam member are interconnected together.

6. A combination as set forth in claim 4 wherein said support frame has opposed wall means, said guide member having

opposed guide surfaces respectively guided by said opposed wall means during movement of said guide member.

7. A combination as set forth in claim 1 wherein said lever means and said guide member are integral.

8. A combination as set forth in claim 6 wherein said support frame has a slot means passing therethrough and defining said opposed end wall means thereof.

9. In combination, a support frame, piezoelectric crystal means carried by said support frame and being adapted to have the stresses thereof altered to create ignition sparks and the like, said crystal means having an end surface, said frame having an end surface facing said end surface of said crystal means and being spaced therefrom, a cam member disposed between said end surfaces and being in engagement therewith, and means for rotating said cam member relative to said end surfaces to vary the distance therebetween and thereby vary the effective force of said cam member acting on said end surface of said crystal means to alter the stresses thereof, said last-named means being directly guided in its movement by said frame to not only rotate said cam member relative to said frame, but also to move the axis of rotation of said cam member relative to said frame, said last-named means comprising a guide member carried by said cam member, said support frame having opposed wall means, said guide member having opposed guide surfaces respectively guided by said opposed wall means during movement of said guide member, said support frame having a slot means passing therethrough and defining said opposed end wall means thereof, said guide member having opposed notches therein respectively defining said guide surfaces thereof, said notches respectively receiving said end wall means of said support frame.
